NOSE PUMP

Quan Hor, Boston, Mass.

Application August 11, 1944, Serial No. 549,061

2 Claims. (Cl. 128—206)

1

This invention relates to a nose pump especially adapted for forcing medicated air into the nostrils of the nose when congested and the primary object of the invention is the provision of a device of this character which will be simple to operate and very inexpensive to manufacture, consequently permitting the distribution thereof at a low cost.

With these and other objects in view as will become more apparent as the description proceeds, the invention consists of certain novel features of construction, combination and arrangement of parts as will be hereinafter more fully described and claimed.

For a complete understanding of my invention, reference is to be had to the following description and accompanying drawing, in which:

Figure 1 is a top plan view illustrating a nose pump constructed in accordance with my invention;

Figure 2 is a side elevation illustrating the device;

Figure 3 is a vertical sectional view illustrating the device.

Referring in detail to the drawing, the numeral 5 indicates an air bellows, while 6 represents spaced tapered air discharge elements having communication with one end of the bellows and in which is arranged medicated material 7 preferably in the form of raw cotton impregnated with a selected medicine. Thumb and finger straps 8 and 9 are secured to the bellows to facilitate the handling and operation of the latter. Air intake openings 10 are formed in opposite walls of the bellows and discharge openings 11 are provided at one of the end walls, placing the air discharge elements 6 in direct communication with the interior of the bellows. Flap type valves 12 may be provided for the inlet openings 10 adapted to permit air to enter the bellows freely, but which will close and prevent the escape of air through the openings 10 when the bellows is collapsed. If desired, the flap valves 12 may be omitted and the openings 10 controlled by the index finger and thumb of the operator's hand.

The bellows 5 is of a box-like construction of substantially rectangular shape including top and bottom walls 13 and 14, end walls 15 and 16 and side walls 17, all of integral construction. The end wall 16 and the side walls 17 have creases therein so that the top and bottom walls may be made to flex towards and from each other under manual pressure. The end wall 15 has the openings 11 therein to place the air dis-

2

charge elements 6 in direct communication with the interior of the bellows.

If desired, the thumb and finger straps may be constructed of a single length of material which has its ends secured to the top and bottom walls and then secured to the end wall 16 to strengthen or reinforce the latter.

The use of the flap valves 12 in this device will prevent the entrance of foreign matter to the interior of the bellows when the device is idle.

While the device may be constructed of any material suitable for the purpose, it is preferable that it be made of strong paper in order that the manufacturing cost of the device may be held to a minimum.

In use, the elements 16 are inserted in the nostrils of the nose and the top and bottom walls moved towards and from each other by the operator to force air through the medicated material 7 into the nostrils to relieve congestion of the nose.

While I have shown and described the preferred embodiment of my invention, it will be understood that minor changes in construction, combination and arrangement of parts may be made without departing from the spirit and scope of the invention as claimed.

Having thus described my invention, what I claim is:

30. 1. In a nose pump, a substantially rectangular box like construction including creased walls to form a bellows construction and having air intake and outlet openings, substantially conical shaped elements carried by one end of the box like construction over the outlet openings, medicated material in said elements, and thumb and finger straps secured to the box like construction, and of a single strip formation said strip being secured to opposite walls of the box like construction and one of the end walls thereof.

35. 2. In a nose pump, a substantially rectangular box like construction including creased walls to form a bellows construction and having air intake and outlet openings, a substantially conical shaped element carried by one end of the box like construction over the outlet openings, medicated material in said element, and thumb and finger straps secured to the box like construction, and of a single strip formation, said strip being secured to opposite walls of the box like construction and one of the end walls thereof, and flap valves for the intake openings.

QUAN HOR.
